TOY IRON

Martin L. Blumenthal, Summit, N.J., assignor to De Luxe
Reading Corporation, a corporation of New Jersey

Filed May 17, 1966, Ser. No. 2,331

Term of patent 7 years

(Cl. D34—15)

FIG. 1

FIG. 2

FIG. 3

FIG. 4

FIG. 5

FIG. 6

FIG. 1 is a top plan view of a toy iron showing my new design;

FIG. 2 is a side elevational view;

FIG. 3 is a front elevational view;

FIG. 4 is a bottom plan view;

FIG. 5 is a rear elevational view; and

FIG. 6 is a fragmentary view looking in the direction of the arrows 6—6 in FIG. 2.

I claim:

The ornamental design for a toy iron, substantially as shown.
